JAMES A. BUTLER, OF NEEDHAM, MASSACHUSETTS, ASSIGNOR TO PNEUMATIC SCALE CORPORATION, LTD., OF NORFOLK DOWNS, MASSACHUSETTS, A CORPORATION OF MASSACHUSETTS.

PACKAGE-LABELING MACHINE.

Application filed April 27, 1923. Serial No. 635,169.

This invention relates to package labeling machines of the general type of the Jagenberg drum labeler. In such a machine, the labels are stacked in a label hopper which is disposed beneath and raised in properly timed relation to the feed of an intermittently revoluble gluing drum of polygonal form whereby to press the uppermost label in the stack against the undermost face of the drum. In a succeeding phase of rotation of the drum, the label is pressed or flattened against the drum face and when said drum face reaches a definite position in its cycle of rotation, the label is automatically stripped from the drum by a label gripper mechanism and held in position for application to the package for which it is intended. The packages are intermittently fed in timed relation to the label feed so that each package meets the label intended for it at the labeling head of the machine where the label is wrapped around the package and the labeled package ejected from the labeling head.

Heretofore such machines have been open to the objection that if for any reason a label was not fed at each cycle of the machine, the label presser would swing directly against the adhesively coated face of the glue drum, instead of against the label on said face, and would itself be coated with glue, unless the operative noticed the failure of label feed in time and grasped and bodily held back the label presser from contact with the glue drum. Whenever the label presser thus became coated with glue, it was necessary to stop the machine and remove the glue from the label presser before the machine could again function properly. Moreover, when the label feed failed, the package for which said label was intended would continue to feed through the machine and would not receive a label, unless the failure of the label feed was noticed in time by the operative and the package bodily removed from the package feed chain before it entered the labeling head. On the other hand, if for any reason a package was not in position upon the intermittently revoluble package feed chain to receive the label intended for it, the label would be fed to the labeling head, unless the failure of feed was noticed in time by the operative and the wrapper stripped from the glue drum by the opera-

tive before it reached said head. If the label reached the labeling head, it so interfered with the action of the labeling mechanism at said head as to require that the machine be stopped until the extra label could be removed.

To the end therefore of overcoming these objections I have devised my present invention. According to my invention, I treat the operation of the machine from both a no-label and a no-package condition.

The existence of a no-label condition is instantly indicated by a no-label detector which is normally disposed in the path of movement of the labels on the glue drum for contact by each label as the faces of said drum are intermittently revolved past said detector. The no-label detector dominates the label presser plate and also a rotatable device controlling the operation of the package feed mechanism. So long as the label feed is uninterrupted, the contact of the labels on the glue drum with the no-label detector will be ineffective upon said detector, but whenever a no-label condition exists, the failure of label contact with said detector will leave the detector in position to prevent the label presser plate from functioning, and will actuate a connecting rod from the cam lever for the label presser plate to the rotatable package feed control device to cause said control device to assume a position wherein the feed mechanism for intermittently advancing the package chain is rendered ineffective so long as the failure of label feed continues.

The existence of a no-package condition is instantly indicated by a no-package detector which is located adjacent the last package space on the package chain for contact by each package as it is placed upon said chain. So long as the last package space on said chain is occupied by a package, the no-package detector is ineffective, but whenever said space is unoccupied, i. e., a no-package condition prevails as regards said space, the failure of package contact with said detector will leave the detector in position to prevent advance of the package chain until the failure of packages is corrected. Moreover, the glue drum will be locked against rotation, the label hopper will be locked against feeding movement relative to the glue drum, the label gripper fingers

- will be prevented from closing upon the label at that face of the drum opposite said fingers, the rotatable package feed control will be locked against rotation; so as to prevent actuation of said control device by the mechanism, which ordinarily actuates it when a no-label condition exists, and the no-label indicator or detector will be prevented from functioning.
- 10 The several safety locks have therefore an interrelated action to each other effective to safeguard the machine against either a no-label or a no-package condition, and while entirely automatic in their operation are themselves dominated by certain hand controls whereby either a no-label or a no-package condition can be deliberately produced by the operative whenever desired, as for example in starting the machine, at which time the glue drum is revolved several revolutions before the labels or packages are fed in order to assure that all faces thereof will be adequately coated with glue, and in finishing the run of the packages through the machine, at which time the label feed is stopped by the operative at the moment that the remaining packages on the package feed chain coincide with the remaining number of labels already pressed against the faces of the glue drum.
- 15 The construction and operation of my invention, together with an embodiment thereof which well illustrates the principles involved, is described and shown in the accompanying specification and drawings, throughout which like reference characters are correspondingly employed and the characteristic features of novelty are particularly pointed out in the appended claims.
- 20 For the purposes of this application I shall show and describe my invention in its adaptation to a Jagenberg drum labeler machine, although it will be understood that such treatment is purely illustrative and in no way limiting. In these drawings, therefore,

Figs. 16 to 21, inclusive, are diagrammatic views illustrating the position of the parts during the cycle of the machine, Fig. 16 showing the start of the glue drum, Fig. 17 the start of the package feed, Fig. 18 the start of the label feed, Fig. 19 the position of the parts when the last package has been fed to the package chain, Fig. 20 the position of the parts when a no-label condition exists, and Fig. 21 the position of the parts when a no-package condition exists, and Fig. 22 is a fragmentary perspective view particularly illustrating the action of the no-label detector, and Fig. 23 is a fragmentary detail view particularly illustrating the stop

pin for limiting the upward movement of the retarding latch 101.

I have indicated at 1 an intermittently revoluble package feed chain having spaced feed lugs 29 between which the packages P are adapted to be centered. The feed chain 1 operates in a feed way 2 (Fig. 1) delivering to the labeling head 3 of the machine.

The labels L are stacked in a vertically disposed label hopper 4 (Fig. 2) which is adapted to be intermittently raised and lowered relative to the undermost face of an intermittently revoluble glue drum 5 of polygonal form whereby to press the uppermost label in the stack against the glue drum.

Each label is afterwards pressed flatly against the drum face by a swinging label presser 49, and when said face reaches the label pick-off phase in the cycle of rotation 20 of the glue drum, the smoothed and flattened label is automatically stripped from the drum by a gripping mechanism, indicated generally at 6, Fig. 2, which is advanced towards and withdrawn from said drum at each cycle of the machine and is adapted upon its forward motion to close upon and peel the label from the drum and upon its rearward motion to open and release the label so that the label may be applied to the package intended for it.

The packages are successively removed from the discharge end of the feed chain 1 by a reciprocating pusher 7 (Fig. 2) which lays each package over a lifting plunger 35 adapted to raise the package against the overlying label, the label being first pressed against the upper face of the package by a downwardly moving plunger 8 which thereupon recedes with the lifting plunger to carry the package and label upwardly past a series of brushes which wipe the label about the package. The labeled package is afterwards ejected from the labeling head along a delivery chute 9 by a reciprocating package ejector 10.

Drive.—I have indicated at 11 (Figs. 1 and 2) the power shaft of the machine. Said shaft may be driven from any suitable power source, either by the pulley 12 or by the gear 11', and the drive may be applied and disconnected at will by means of a clutch 12' and a clutch shifting mechanism 13 operated from a pair of shipper levers 14.

The drive shaft 11 has a pinion 15 thereon meshing with a gear 16 on a cam shaft 17 journaled longitudinally of the machine. The package pusher 7 and package ejector 10 are actuated from drum cams 200 and 201, respectively, on said cam shaft and the downwardly moving package plunger 8 is actuated from a cam 202 on said cam shaft.

Package feed.—When the machine is functioning properly, the package feed chain 1 is intermittently advanced one package space at each revolution of the cam shaft 17. To

this end, the shaft 19 (Fig. 3) for the driving sprocket 20 of said chain has fast thereon a feed ratchet 21. Fulcrumed upon the sprocket shaft 19 is a pawl lever 22 having at its upper end a pawl 23 adapted to engage the ratchet teeth. At its lower end the pawl lever is connected by a rod 24 to a rocker lever 26' on a rock shaft 26 journaled longitudinally of the machine in rear of the cam shaft 17. The lever 26' is connected by a rod 27 with an eccentric 28 on the cam shaft 17.

Glue drum.—Journaled above the cam shaft 17 and intermittently actuated therefrom is the shaft 18 for the glue drum 5. Fast on the glue drum shaft is a ratchet 30 (Fig. 3) with which engages a feed pawl 31 pivotally mounted upon a cam lever 32. The lever 32 is fulcrumed upon the glue drum shaft and carries a cam roll 33 disposed for actuation by a cam 34 on the cam shaft whereby the ratchet 30 is turned one tooth space at each revolution of the cam shaft.

In order to prevent shifting of the glue drum after each actuation of the feed pawl 31, I provide a drum locking pawl 37 which is drawn towards the feed ratchet 30 by a tension spring 371 (Fig. 2) so as to engage in a notch of the feed ratchet at substantially the moment that the feed pawl 31 is withdrawn from said ratchet thereby positively locking the glue drum at each step in its cycle of rotation. The locking pawl 37 is disengaged from the ratchet 30 by a cam 38 on the cam shaft 17, (Fig. 2).

The glue drum 5 revolves relative to a glue pan 35 (Fig. 7) and is supplied with glue therefrom by intergeared transfer rolls 36.

Label feed.—The labels L are stacked in the label hopper 4 and said hopper is moved towards and from the glue drum at each revolution of the cam shaft 17 whereby to press the uppermost label of said stack against the undermost face of the glue drum. To this end, the label hopper lifting plunger 47 (Fig. 2) is tensioned by heavy coil springs 48 which normally raise the hopper towards the drum. The hopper is returned at each revolution of the cam shaft by a cam 39 (Fig. 5) on said shaft which bears against a cam roll 40 on a rocker arm 41 fast at one end of a rock shaft 42. At its opposite end the shaft 42 has fast thereon an arm 43 (Fig. 7) adapted to bear upon a pin 44 at one end of a lever 45. The lever 45 is slotted between its ends to engage over a stud 46 on the label hopper lifting plunger 47 whereby to hold said plunger down against the action of the tension springs 48.

Label presser.—After the label hopper has been raised to transfer the uppermost label in the stack to the glue drum and has again lowered the label presser plate or flattener 49 (Fig. 3) is automatically moved against

the face of the drum opposite it, whereby to press the label flatly against said face. To this end the label presser is clamped to a cross rod 50 (Fig. 2) which connects a pair of vertical rocker levers 51 and 52 mounted upon alined rock shafts 53 and 54. Fast on the rock shaft 53 is an operating lever 55 having a cam roller 56 normally drawn towards an open cam 57 on the cam shaft 10 by a tension spring 58.

The actuation of the cam 57 is transmitted from the rock shaft 53 to the rock shaft 54 by an arm 60 (Fig. 2) on the shaft 53, a connecting rod 61 and a rocker arm 62 connected to said rod and fast to a rock shaft 63 journaled in rear of the rock shafts 53 and 54. Fast upon the rock shaft 63 is a rocker arm similar to the rocker arm 62 and connected by a rod to an extension 64 on the rock shaft 54, whereby the rocker levers 51 and 52 are swung in unison at each actuation of the cam lever 55 and rock the label presser 49 towards and from the glue drum.

Label gripper.—The label gripping mechanism is mounted upon a horizontally disposed slide 65 (Fig. 7) guided in a slide frame 66 and reciprocated towards and from the glue drum in properly timed relation to the rotation thereof by a link 67 which is connected at one end to said slide and at its opposite end to a rocker lever 68 on the rock shaft 26. Fast on the opposite end of said rock shaft is a rocker lever 69 (Fig. 1) which is linked at 70 to a cam lever 71 having a cam roller 72 operating in the groove of a closed cam 73 (Fig. 2) on the cam shaft.

The label gripping mechanism comprises a relatively stationary gripping plate 74 (Fig. 7) and a superposed series of spaced relatively movable gripper fingers 75 which are yieldably urged towards said plate by springs 76 (Fig. 2) coiled about projections on the fingers themselves. The gripper fingers are mounted upon a rock shaft 77 which is journaled in bearings rising from the gripping plate and is rocked in properly timed relation to the rotation of the glue drum to close the fingers upon the label after they enter the pick-off slots 90 in the faces of the drum upon the forward throw of the slide 65 and to open said fingers to release the label when the slide is retracted.

To this end the rock shaft 77 has fast thereto a lever 78 which is connected by a rod 79 to one arm of a bell crank lever 80 pivotally mounted upon the same rocker lever 68 which reciprocates the gripper slide 65 towards and from the glue drum. The opposite arm of the bell crank lever 80 is connected by a rod 81 (Fig. 12) to one end of a lever 84, which is fulcrumed between its ends on a rock shaft 83. Fast on the opposite end of the lever 84 is a cam roller 85 disposed for actuation by a cam 86 (Fig. 2) on the cam shaft 17.

No-label detector.—According to my present invention whenever a no-label condition exists, the label presser 49 is automatically held out of operation and the rotation of the package feed chain is automatically prevented so that the package to which the label would have been applied is held back from the labeling head until the next label is properly fed. To this end I provide a no-label indicator or detector 89 (Fig. 11) 70 adapted to instantly indicate the failure of label feed, and as contemplated herein operating in the same slots 90 at the meeting edges of the several faces of the glue drum within which the label gripper fingers are adapted to enter in order to grasp and withdraw the label from the drum as each face of the drum reaches the pick-off position in its cycle of rotation.

The detector 89 is fast upon the right hand end of a rock shaft 91 (Fig. 11 and Fig. 22) journaled longitudinally of the machine parallel to the cam shaft 17 in bearings 92 and 93. Fast upon the left hand end of said rock shaft is a dog 94 (Fig. 4^b 85 and Fig. 22) adapted to enter a notch 95 located between the ends of a latch lever 96 which is pivoted at its rear end to the frame of the machine at 97, and is adapted to be contacted and lifted at each cycle of operation of the machine by a bumper cam piece 99, in Fig. 4, on the cam 57 which operates the cam lever 55 for the label presser 49. Pivoted at 100 (Fig. 4^a) to the forward end of said latch lever is a spring-pressed retarding latch 101 adapted to normally clear the bent upper end 102 of the lever 55. The spring for the latch 101 is designated at 101' 90 in Figs. 4^a and 22. In order to limit the extreme upward movement of the latch 101, 10 said latch adjacent the end opposite the latching end is cut out as indicated at 300. The cut-out 300 is adapted to abut against a stop pin 301 carried by the lever 96 so that when the dog 94 is down, as where 100 there is a label on the drum, the retarding latch is prevented from moving upward far enough to catch on the end 102 of the cam lever 55.

Fast on the rock shaft 91 beyond the bearing 92 is a counterweight lever 104 (Fig. 4^a and Fig. 22) into which is threaded at one end a screw 105 having adjustable counterweights 106 thereon whereby the balance of said lever 104 may be varied. The other end of the lever 104 is adapted to contact an adjustable gage screw 107 mounted on a block 92' fastened to said bearing plate 92. The counterweight lever 104 normally causes the no-label detector 89 to lie in position to enter the nearest slot of the series of slots 90 in the glue drum faces as each face is successively rotated therewith.

When the feed of the labels is normal, the physical presence of the label itself will lift

the detector 89 out of said slot, rocking its shaft 91 towards the front in Fig. 2 against the action of said counterweight lever 104, and the latch dog 94 will therefore be moved 5 in position to enter the locking notch 95 of the latch lever 96 which in the meantime has been lifted by the cam piece 99 on the cam 57. This allows the bent upper end 102 of the lever 55 to pass freely over the 10 top of the retarding latch 101 (Fig. 3) and hence the label presser plate is not prevented from operating.

When a no-label condition exists, however, the detector finger 89 will not be rocked and 15 the latch dog 94 will not be carried into position to enter the locking notch of the latch lever 96 when the cam piece 99 passes from beneath said lever. The locking dog will therefore prop up the latch lever and 20 the retarding latch 101 will remain in the path of the bent upper end 102 of the cam lever 55 (Fig. 4^a) so that the tension spring 58 cannot keep the cam roller 56 of said lever in contact with the cam 57 and hence 25 the label presser 49 will be prevented from swinging against the glue drum.

Automatic package feed control.—When a no-label condition exists and the operating lever 55 for the label presser 49 is held out 30 of operation, the package to which the label would have been applied is held back from the labeling head until the next label is properly fed. To this end, the cam lever 55 is connected by a rod 111 with a rotatable 35 package feed control, indicated generally at 108, Fig. 1, and effective whenever the lever 55 is held out of operation to interpose a ratchet shield 110, carried by an arm 109 which is fulcrumed on the sprocket shaft 19 40 for the package feed chain 1, between the feed pawl 23 and the sprocket driving ratchet 21 whereby to prevent advance of 45 said feed chain so long as the no-label condition exists.

As here shown, the rear end of the rod 111 is connected to a cam throw-off lever 112 (Fig. 8) which carries at its lower end a pin 113 extending through a slot in the rear end of said connecting rod. Anchored to 50 said pin and the connecting rod 111 is a coil spring 114 adapted to allow the connecting rod to move forwardly when the label presser lever 55 operates at its extreme outward throw. The upper end of said cam throw-off lever 112 is provided with a pin 115 projecting through an arcuate slot 116 in a fixed 55 casing 117 which is supported upon the bed plate of the machine. The slot 116 is a clearance slot to permit the play of the cam throw-off lever and one end of said slot also constitutes a limiting stop to check the motion of said lever in one direction. The lever is checked in its opposite direction by a stop pin 118 projecting from the fixed 60 casing 117 into the path of said lever.

The pin 115 is disposed in the path of a series of double-ended dogs 119 which are pivoted between their ends at 120 to a rotating disc 121 mounted within said fixed casing and driven from the cam shaft of 70 the machine by a sprocket 122 loose on the stub shaft 123 which carries said disc.

The sprocket 122 is connected by a chain 131 to two idler sprockets 132 and a sprocket chain 133 connects one of these idlers with 75 a driving sprocket 134 on the cam shaft (Fig. 4). The driving ratio between the rotating disc and the cam shaft is in direct relation to the number of faces of the glue drum between the face at which the label 80 presser 49 operates and the face at which the label gripper fingers strip the label from the drum.

When the lever 55 is held out of operation, due to a no-label condition, the cam throw-off lever 112 will be rocked on its pivot to bring its dog-actuating pin 115 into the path of the rotating dogs 119 so that when one of said dogs contacts said pin the opposite end of the dog will be swung upwardly against 90 one of a series of spring-tensioned cam pieces 135 (Fig. 8) which are pivotally mounted at 136 at one end upon the fixed casing. The cam piece thus actuated will be projected beyond the periphery of the rotating disc against the tension of its spring 135' into the path of a cam roller 137 which is carried by an arm 138 fast on a rock shaft 139 journaled in suitable bearings adjacent 95 the fixed casing 117. At its opposite end 100 said rock shaft 139 is provided with an arm 140 which is connected by a rod 141 with the ratchet shield carrying arm 109. The cam roller 137 is normally held against the periphery of the disc by a coil spring 142 105 (Fig. 8). This spring also tensions the lever 140 so as to return said lever after actuation thereof by a cam 135. The shield carrying arm will therefore be rocked forwardly 110 against the action of the spring 142 to interpose its shield 110 between the feed pawl 23 and the ratchet 21 thereby preventing advance of the package feed chain 1. After one of the cam-actuating dogs is tripped it is automatically reset during the continued 115 rotation of the disc by a resetting pin 143 disposed in the path of the tail end of said dog.

When, therefore, a no-label condition exists, the label presser 49 is automatically 120 held out of operation and the advance of the package feed chain 1 is prevented until the failure of label feed has been corrected.

No-package detector.—According to my invention, when through failure of the package delivery there is no package in the last package space of the feed chain 1, the advance of said chain is stopped until a package has been fed. To this end I mount at 125 the last package space of the chain a pack- 130

age detector 144 which, as here shown, is formed as a finger fast on a rock shaft 146 journaled through one of the side rails constituting the package feedway 2 and counterbalanced as indicated at 145 to normally stand in the path of the packages for depression against the action of its counterweight by each package as it passes over said finger. The outer end of the rock shaft 146 is provided with a flat cam surface 147 beneath which rests the forward end of the latch dog 148. Said dog is pivoted between its ends at 149 and is overbalanced at its rear end so that its forward end tends to constantly project against said cam surface 147.

The rear end of the latch dog 148 is provided with a hook 150 adapted to play relative to the latching point of the vertical 20 arm 151 of a bell crank lever 152. The lever 152 is pivoted between its ends at 153 and is spring-tensioned as indicated at 152'. The horizontal arm 154 of the lever 152 terminates in a latching point 155 adapted 25 to play between the forward edge of a latch shield arm 156 and a cam piece 157 fast to and spaced from said arm. The arm 156 is fulcrumed upon the sprocket shaft 19 for the package feed chain and carries a ratchet 30 shield 158 adapted to play over the feed ratchet 21 for said chain. Projecting from said arm is a lug 159 adapted to be contacted by the feed pawl lever 22 before said lever reaches the limit of its rearward motion. Below its fulcrum 19, the arm 156 is connected by a rod 161 with a bell crank 35 lever 162 which is fulcrumed at 163 and is spring-tensioned as indicated at 160.

The spring 160 constantly tends to draw 40 the arm 156 forwardly so that the shield 158 will be interposed between the ratchet 21 and feed pawl 23, but normally the tension spring 152' for the bell crank 152 is holding said lever in such position that the 45 latching point 155 thereof will lie between the arm 156 and cam piece 157 and will prevent the shield from being carried far enough forward to cover the ratchet (see Fig. 6).

50 When the feed of the packages onto the chain 1 is normal, each package depresses the detector 144 as it passes thereover and in such passage lifts the latching end 150 of the dog 148 away from the bell crank lever 152, (Fig. 6), thus allowing the latching point 155 of said lever to be rocked, by the spring 152', into the path of the shield arm 156 whereby to prevent said arm from being rocked forwardly, by the spring 160, 55 far enough to cause the shield 158 to cover the feed ratchet 21. The feed pawl 23 may therefore engage and rotate said ratchet one tooth space at the next forward throw of the feed pawl lever 22 whereby to advance

the package feed chain. Such advance removes the package from the detector, which thereupon automatically returns to the position of Fig. 5^a. Upon the return stroke of the feed pawl lever 22, said lever will contact the projection 159 of the ratchet shield 65 arm 156 and will carry said arm and with it the ratchet shield 158 rearwardly against the action of the tension spring 160 sufficiently far to expose the feed ratchet 21 to the pawl 23 so that the pawl may engage 70 and rotate the ratchet one tooth space upon the next forward throw of the pawl lever 22. The same contact of the lever 22 and projection 159 also causes the cam piece 157 to lift the latching point 155 of the bell 75 crank lever 152 away from the ratchet shield arm so as to latch said lever to the dog 148 as shown in Fig. 5^a.

If no package occupies the last package 80 space of the feed chain, the detector 144 is not depressed and the bell crank lever 152 remains latched in the position of Fig. 5^a by the engagement of its vertical arm 151 with the hook end 150 of the latch dog 148. The latching point 155 is thus removed from the 85 path of the shield arm 156 so that said arm may be swung forward by the tension spring 160 to interpose the shield 158 between the feed ratchet 21 and pawl 23 and prevent the pawl from engaging the ratchet and advancing 90 the feed chain.

The forward movement of said arm 156 through the connecting rod 161 rocks the bell crank lever 162 forwardly, and such movement of the bell crank lever automatically applies a series of safeties to (1) stop the rotation of the glue drum; (2) prevent the label hopper from feeding; (3) prevent the gripper fingers from closing; (4) stop the rotation of the package feed control; 100 and (5) prevent the no-label detector from functioning. These several safeties are all applied simultaneously with the arrest of the package feed chain.

Glue drum lock.—When a no-package condition exists and the bell crank lever 162 has been rocked forwardly, an arm 164 (Fig. 5) fast on the pivot shaft for said lever is carried forwardly therewith to cause the glue drum to be locked against rotation. Said arm is linked at 165 to an arm 166 loose on the glue drum shaft. The arm 166 is provided at its free end with a cam surface 167 normally disposed out of the path of a pin 168 projecting from the feed pawl 31 for the glue drum shaft. Upon actuation of said arm 166, the cam 167 will be turned sufficiently to contact the pin 168 and move the feed pawl 31 away from the feed ratchet 30 for the glue drum shaft 110 (Fig. 21) so as to prevent further rotation of said shaft until the failure of the package feed has been corrected, at which time the 115

bell crank lever 162 will be rocked in the opposite direction to withdraw the cam 167 from the pin 168.

Label hopper lock.—The same forward movement of the bell crank lever 162, through a connecting rod 169 fastened thereto, depresses a yieldable lever 170 (Figs. 5 and 21), one arm of which is pinned to a rock shaft 171 and the other arm of which carries a latch 172 (Fig. 5^b) adapted to engage over a latching lug 173 on the actuating lever 41 for the label hopper whereby to lock the hopper against feeding movement whenever a no-package condition exists.

Gripper finger lock.—When the rock shaft 171 is turned, by depression of the lever 170, a latch 174 (Fig. 12) fast on the opposite end of said shaft is carried over a pin 175 on the cam lever 84 for opening the gripper fingers. The lever 84 is therefore locked against actuation by the cam 86 so long as the no-package condition exists.

Clutch shift for rotatable package feed control.—Slidable on and keyed to the hub of the driving sprocket 122 for the rotatable package feed control 108 is a sleeve 124 (Fig. 9^a) having a driving pin 129 adapted to engage in one of a series of driving openings 130 formed in the adjacent face of the rotatable disc 121 of said control. Pivoted at 125^b to one of the bearings for the sprocket shaft 123 is a clutch yoke 125. Both ends of said yoke are forked and provided with pairs of spaced alined pins 126. The lower pin pair engages and actuates the sliding sleeve 124. The upper pin pair engages a double-threaded worm 127 formed on a rock shaft 128 journaled above the sprocket shaft 123.

When a no-package condition exists, and the bell crank lever 162 has been rocked forwardly, an arm 176 (Fig. 4) fast on the pivot shaft for said lever is also rocked forwardly to disengage the drive pin 129 from the rotating disc 121. Said arm is linked at 177 to an arm 178 yieldably mounted on the rock shaft 128 whereby to rock said shaft and with it the yoke 125 so as to withdraw the pin 129 from the driving openings 130 of the disc 121, thus preventing further rotation of said disc.

In order to positively lock the disc against rotation after the yoke 125 has been rocked to disengage the driving pin 129, the yoke 125 is provided above its pivot with a locking pin 125' adapted to enter in one of a series of spaced locking notches 125^a formed in the periphery of said disc. By arranging the driving and locking pins 129 and 125', respectively, below and above the pivot for the yoke 125 it results that the same movement of the yoke in one direction, simultaneously withdraws the driving pin from and

engages the locking pin with the disc, and vice versa.

No-label detector lock.—When a no-package condition exists and the bell crank lever has been rocked forwardly, an arm 179 (Fig. 4) on the shaft 163 for said lever is rocked forwardly to cause the no-label detector 89 to be locked out of action. The arm 179 is linked at 180 to a latch 181 (Fig. 4^a) which is fulcrumed between its ends at 182 to the bearing plate 92 for the no-label detector shaft 91. At its forward end the latch 181 is adapted to rest upon a latch lever 183, also fulcrumed upon the plate 92. The lever 183 terminates in a latching shoulder 184 adapted to drop onto a dog 185, see Fig. 4^b, mounted upon the shaft 91 when the arm 179 is rocked forwardly and the engagement of said dog 185 with said shoulder 184 prevents said shaft from being rocked towards the glue drum 5 by its counterweight. The no-label detector will therefore be prevented from entering the slot of the glue drum face opposite it and the retarding latch 101 will be prevented from interfering with the action of the label presser operating lever 55.

Starting movement.—The shipper lever for the clutch at the drive shaft is first rocked to throw in the clutch and start the rotation of the cam shaft. This shaft rotates continuously but the several safety devices with which the machine is equipped are all effective because at this time both a no-label and a no-package condition exist.

In starting the machine, the operative usually runs the glue drum a few revolutions to insure that all faces thereof will be coated with glue before the labels and packages are fed. To this end I provide a dominant hand lever 186 (Fig. 5^c) which is loosely mounted by a pin and slot connection 253 at one end of a rock shaft 187. Loosely mounted by a pin and slot connection 251 upon the opposite end of said shaft is a latch 188 which is adapted to drop onto the top of the moving bell crank lever 162 and latch said lever against motion. The hand lever 186 is a weighted lever and is always disposed at one or the other side of the vertical so that it may gravitate in either direction when thrown by the operative. This is necessary because the spring-tensioned shield carrying arm 156 which actuates the bell crank lever 162 is constantly in intermittent motion and hence the bell crank lever is not always in position to be effectively latched by the latch piece 188 when the hand lever is swung to throw the latch piece down onto the bell crank lever. The latch piece simply therefore drops upon the top of the bell crank lever and rides over behind it into effective latching position as the hand lever continues to gravitate to its lowest position.

After the glue drum has been sufficiently

coated with glue, the hand lever 186 is rocked in the opposite direction to release the bell crank lever 162. Inasmuch as a non-label condition still exists, however the ratchet shield 110 will still be interposed between the feed ratchet 21 and the feed pawl 23 for the package chain so as to prevent said chain from advancing (Fig. 17). To overcome this safety lock, I provide a dominant hand lever 191 which is linked at 192 to the cam throw-off lever 112 (Fig. 8) and upon actuation draws the pin 115 of said lever 112 out of the path of the dogs 119 so that the cam roll 137 will not be actuated by the rotating cams 135. The shield 110 will now be drawn backwardly by the tension spring 142 to expose the feed ratchet 21 to the feed pawl 23 so that the package feed chain may be advanced.

29 The operative now starts the feed of the labels by throwing in the usual hand starting lever 189 (Fig. 7) to permit operation of the label hopper. This lever is pivoted at 190 and has a cam face adapted when the starting lever is thrown down to release the tail of the label hopper locking lever 45 and when the starting lever is thrown up to engage and lock said lever 45 against the lifting action of the elevating springs for the 30 label hopper.

35 In completing the run of the machine the operative counts the packages remaining on the package chain and when the package number is equal to the number of labels remaining on the glue drum, the label starting lever 189 is thrown up to prevent the feed of any more labels, and the hand lever 186 is thrown down to again latch the bell crank lever 162 and permit the feed chain to advance the remaining packages thereon through the labeling head.

45 Various modifications in the form and construction of my machine may obviously be made without departing from the spirit of my invention if within the limits of the appended claims.

What I therefore claim and desire to secure by Letters Patent is:

50 1. In a labeling machine, the combination with a glue drum, a label feeder, a label presser, and mechanism for operating said elements in timed relation to each other, of means for automatically preventing operation of the label presser upon a failure of label placement on the glue drum.

55 2. In a labeling machine, the combination with a glue drum, a label feeder, a label presser, a package feeder, and mechanism for operating said elements in timed relation to each other, of means for automatically preventing operation of both the label presser and the package feeder upon a failure of label placement on the glue drum.

60 3. In a labeling machine, the combination with a glue drum, a label feeder, a label

presser, a package feeder, and mechanism for operating said elements in timed relation to each other, of means for automatically preventing operation of both the label presser and the package feeder upon a failure of label placement on the glue drum, and means for automatically preventing operation of both the label feeder and the package feeder upon a failure of package placement on the package feeder. 70

75 4. In a labeling machine, the combination with a glue drum, a label feeder, and mechanism for operating said elements in timed relation to each other, of automatically operative means acting independently of the quantity of labels in the label feeder to prevent operation of the package feeder whenever the label feeder for any reasons fails to place a label on the glue drum. 80

85 5. In a labeling machine, the combination with a glue drum, a label feeder, a package feeder, and mechanism for operating said elements in timed relation to each other, of automatically operative means acting independently of the quantity of labels in the label feeder to prevent operation of both the label feeder and the package feeder whenever the label feeder for any reason fails to place a label on the glue drum. 90

95 6. In a labeling machine, the combination with a glue drum, a label feeder, a label presser, and mechanism for operating said elements in timed relation to each other, of means for automatically preventing operation of the label presser upon a failure of label placement on the glue drum, and a semi-dominant hand control for deliberately producing a no-label condition. 100

105 7. In a labeling machine, the combination with a glue drum, a label feeder, a label presser, a package feeder, and mechanism for operating said elements in timed relation to each other, of means for automatically preventing operation of both the label presser and the package feeder upon a failure of label placement on the glue drum, means for automatically preventing operation of the label feeder and the package feeder upon a failure of package placement on the package feeder, a semi-dominant hand control for deliberately producing a no-label condition, and a dominant hand control for overcoming such condition. 110

115 8. In a labeling machine, the combination with a glue drum, a label feeder, a label presser, and mechanism for operating said elements in timed relation to each other, of means automatically effective upon a failure of label placement on that face of the glue drum opposite said label presser to prevent operation of said label presser. 120

125 9. In a labeling machine, the combination with a glue drum, a label feeder, a label presser, a package feeder, and mechanism for operating said elements in timed relation to 130

each other, of means automatically effective upon a failure of label placement on that face of the glue drum opposite said label presser to prevent operation of both said label presser and said package feeder.

10. In a labeling machine, the combination with a glue drum, a label feeder, a label presser, a package feeder, and mechanism for operating said elements in timed relation to each other, of means automatically effective upon a failure of label placement on that face of the glue drum opposite said label presser to prevent operation of both said label presser and said package feeder.

15. In a labeling machine, the combination with a glue drum, a label feeder, a label presser, a package feeder, a label gripper, and mechanism for operating said elements in timed relation to each other, of a no-label detector automatically effective upon a failure of label placement on the glue drum to prevent operation of both said label presser and said package feeder, locks for the glue drum, label feeder, label gripper, and no-label detector, and means automatically effective upon a failure of package placement upon the package feeder to prevent operation of the package feeder and to apply the glue drum, label feeder, label gripper, 30 and no-label detector locks.

20. In a labeling machine, the combination with a glue drum, a label feeder, a label presser, a package feeder, a label gripper, and mechanism for operating said elements in timed relation to each other, of a rotatable control for the package feeder, a no-label detector automatically effective upon a failure of label placement on the glue drum to prevent operation of said label presser and to actuate said control whereby to prevent operation of the package feeder, locks for the glue drum, label feeder, label gripper and no-label detector, and means automatically effective upon a failure of package placement upon the package feeder to stop the rotation of said control whereby to prevent operation of the package feeder and to apply the glue drum, label feeder, label gripper, and no-label detector locks.

25. In a labeling machine, the combination with a glue drum, a label feeder, a label presser, a package feeder, a label gripper, and mechanism for operating said elements in timed relation to each other, of a rotatable control for the package feeder, a no-label detector automatically effective upon a failure of label placement on the glue drum to prevent operation of said label presser and to actuate said control whereby to prevent operation of the package feeder, locks for the glue drum, label feeder, label gripper and no-label detector, and means automatically effective upon a failure of package placement upon the package feeder to stop the rotation of said control whereby to pre-

vent operation of the package feeder and to apply the glue drum, label feeder, label gripper, and no-label detector locks, a semi-dominant hand control for deliberately producing a no-label condition, and a dominant hand control for overcoming such condition.

30. In a labeling machine, the combination with an intermittently revoluble glue drum, an intermittently operable label feeder, an intermittently operable label presser, and an intermittently revoluble package feeder, and means for intermittently operating said elements in timed relation to each other, of means automatically applied upon a failure of label placement on the glue drum to prevent operation of the label presser and the package feeder and means automatically applied upon a failure of package placement on the package feeder to prevent operation of the package feeder and the label feeder.

35. In a labeling machine, the combination with an intermittently revoluble faceted glue drum, an intermittently operable label feeder, and an intermittently operable label presser effective to successively press the labels against the face of the glue drum opposite thereto, of a no-label detector co-acting with the labels on said drum as the drum is successively rotated therepast, and a latch controlled by said detector and effective to prevent operation of said label presser upon a failure of label placement on the glue drum.

40. In a labeling machine, the combination with an intermittently revoluble faceted glue drum, an intermittently operable label feeder, and an intermittently operable label presser effective to successively press the labels against the face of the glue drum opposite thereto, of a no-label detector disposed at that point in the orbit of the drum at which the label presser operates and co-acting with the labels on said drum as the drum is successively rotated therepast, and a latch controlled by said detector and effective to prevent operation of said label presser upon a failure of label placement on the glue drum.

45. In a labeling machine, the combination with an intermittently revoluble faceted glue drum, an intermittently operable label feeder, and an intermittently operable label presser effective to successively press the labels against the face of the glue drum opposite thereto, of a no-label detector disposed at that point in the orbit of the drum at which the label presser operates and is successively rotated therepast, and a latch controlled by said detector and effective to prevent operation of said label presser upon a failure of label placement on the glue drum, and a dominant hand control for deliberately producing a no-label condition.

50. In a labeling machine, the combination with an intermittently revoluble glue drum, intermittently operable label and package feeders, and an intermittently op-

- erable label presser effective to successively press the labels against the face of the glue drum opposite thereto, of a no-label detector actuated by the labels on said drum as the drum is successively rotated therepast, a latch controlled by said detector and effective to prevent operation of said presser whenever a no-label condition exists, a control for the package feeder, and an operative connection from the label presser to said control for actuating said control and preventing operation of said package feeder upon a failure of label placement upon the glue drum.
- 15 19. In a labeling machine, the combination with an intermittently revoluble glue drum, intermittently operable label and package feeders, and an intermittently operable label presser effective to successively press the labels against the face of the glue drum opposite thereto, of a no-label detector actuated by the labels on said drum as the drum is successively rotated therepast, a latch controlled by said detector and effective to prevent operation of said presser whenever a no-label condition exists, a control for the package feeder, and an operative connection from the label presser to said control for actuating said control and preventing operation of said package feeder upon a failure of label placement upon the glue drum, and a no-package detector for automatically preventing operation of the package and label feeders upon a failure of package placement on the package feeder.
- 20 20. In a labeling machine, the combination with an intermittently revoluble glue drum, intermittently operable label and package feeders, and an intermittently operable label presser effective to successively press the labels against the face of the glue drum opposite thereto, of a no-label detector actuated by the labels on said drum as the drum is successively rotated therepast, a latch controlled by said detector and effective to prevent operation of said presser whenever a no-label condition exists, a control for the package feeder, and an operative connection from the label presser to said control for actuating said control and preventing operation of said package feeder upon a failure of label placement upon the glue drum, locks for the glue drum, label feeder and no-label detector, and a no-package detector automatically effective upon a failure of package placement upon the package feeder to actuate the control for said feeder whereby to prevent operation of said feeder and to apply the glue drum, label feeder and no-label detector locks.
- 25 21. In a labeling machine, a faceted intermittently revoluble glue drum having label pick-off slots at the meeting edges of its faces, a label feeder, a label presser for successively pressing the labels against the face of the drum opposite thereto, a no-label detector controlling the operation of said presser and disposed opposite the face of the drum at which said presser operates in position to enter one of the label pick-off slots as the drum is rotated therepast and normally prevented from entering said slot by the label on the drum face so as to be ineffective upon the operation of the label presser, but automatically preventing operation of said presser if no label is encountered.
- 30 22. In a labeling machine, a faceted intermittently revoluble glue drum having label pick-off slots at the meeting edges of its faces, a label feeder, a package feeder, a label presser for successively pressing the labels against the face of the drum opposite thereto, a no-label detector controlling the operation of said presser and disposed in position to enter one of the label pick-off slots as the drum is rotated therepast and lifted out of said slot by the label on the drum face so as to be ineffective upon the operation of the label presser but automatically preventing operation of said presser if no label is encountered, and operative connections from said label presser to said package feeder for preventing operation of said package feeder whenever a no-label condition exists.
- 35 23. In a labeling machine, a cam shaft, a faceted glue drum having label pick-off slots at the meeting edges of its faces and intermittently revolved from said cam shaft, a label feeder intermittently operated from said cam shaft, a label presser mounted to swing towards and away from said glue drum, a cam on said cam shaft and a cam lever actuated by said cam for operating said label presser, a no-label detector comprising a rock shaft having a finger disposed to enter one of the label pick-off slots as the drum is rotated therepast and normally lifted out of said slot by the label on the drum face so as to be ineffective upon the operation of the label presser, a locking dog on said rock shaft, a pivoted latch lever having a locking notch adapted to receive said dog, a cam on the cam shaft for raising said latch lever relative to said dog and a retarding latch carried by the latch lever and normally disposed out of the path of the cam lever which actuated the label presser, but movable into interfering position relative to said lever whenever the no-label detector finger fails to encounter a label on the glue drum.
- 40 24. In a labeling machine, a cam shaft, a faceted glue drum having label pick-off slots at the meeting edges of its faces and intermittently revolved from said cam shaft, a label feeder and a package feeder intermittently operated from said cam shaft, a label presser mounted to swing towards and away from said glue drum, a cam on said cam

- shaft and a cam lever actuated by said cam for operating said label presser, a no-label detector comprising a rock shaft having a finger disposed to enter one of the label 5 pick-off slots as the drum is rotated therepast and normally lifted out of said slot by the label on the drum face so as to be ineffective upon the operation of the label presser, a locking dog on said rock shaft, a pivoted latch lever having a locking notch 10 adapted to receive said dog, a cam on the cam shaft for raising said latch lever relative to said dog, a retarding latch carried by the latch lever and normally disposed out of the path of the cam lever which actuated the 15 label presser but movable into interfering position relative to said lever whenever the no-label detector finger fails to encounter a label on the glue drum, a rotating control 20 device for said package feeder and operative connections from said device to the cam lever which actuates the label presser effective to prevent operation of said package feeder whenever a no-label condition exists.
- 25 25. In a labeling machine, a cam shaft, a faceted glue drum having label pick-off slots at the meeting edges of its faces and intermittently revolved from said cam shaft, a label feeder and a package feeder intermittently operated from said cam shaft, a label presser mounted to swing towards and away from said glue drum, a cam on said cam shaft and a cam lever actuated by said cam for operating said label presser, a no-label detector comprising a rock shaft having a finger disposed to enter one of the label 30 pick-off slots as the drum is rotated therepast and normally lifted out of said slot by the label on the drum face so as to be ineffective upon the operation of the label presser, a locking dog on said rock shaft, a pivoted latch lever having a locking notch 35 adapted to receive said dog, a cam on the cam shaft for raising said latch lever relative to said dog, a retarding latch carried by the latch lever and normally disposed out of the path of the cam lever which actuates 40 said label presser, but movable into interfering relation to said lever whenever a no-label condition exists, and operative 45 connections from said lever to the package feed mechanism for preventing advance of the packages whenever a no-label condition exists.
- 50 50. In a labeling machine, a cam shaft, a faceted glue drum having label pick-off slots at the meeting edges of its faces and intermittently revolved from said cam shaft, a label feeder and a package feeder intermittently operated from said cam shaft, a label presser mounted to swing towards and away from said glue drum, a cam on said cam shaft and a cam lever actuated by said cam for operating said label presser, a no-label detector comprising a rock shaft having a finger disposed to enter one of the label 55 pick-off slots as the drum is rotated therepast and normally lifted out of said slot by the label on the drum face so as to be ineffective upon the operation of the label presser, a locking dog on said rock shaft, a pivoted latch lever having a locking notch 60 adapted to receive said dog, a cam on the cam shaft for raising said latch lever relative to said dog, a retarding latch carried by the latch lever and normally disposed out of the path of the cam lever which actuates said label presser, but movable into interfering position relative to said lever whenever the no-label detector finger fails to encounter a label on the glue drum, a control device for said package feeder comprising a rotating disc, a series of cam actuating dogs pivotally mounted thereon a series of pivotally mounted cams normally disposed within the periphery of said disc, a cam throw-off lever having an actuating pin adapted to be moved into the path of said dogs, operative connections from said lever to the cam lever which actuated the label presser, and a cam lever normally held towards the periphery of said disc for actuation by one of said cams whenever a no-label condition exists and effective upon ac- 65 tuation to prevent operation of the package feeder.
26. In a labeling machine, a cam shaft, a glue drum and a label feeder intermittently operated from said shaft, a label presser mounted to swing towards and away from the glue drum, a cam on said cam shaft and a cam lever actuated by said cam for operating said label presser, a no-label detector comprising a rock shaft having a finger and disposed for actuation by the labels upon the glue drum, a locking dog on said rock shaft, a pivoted latch lever having a locking notch 70 adapted to receive said dog, a cam on the cam shaft for raising said latch lever relative to said dog, and a retarding latch carried by said latch lever and normally disposed out of the path of the cam lever which actuates said label presser, but movable into interfering relation to said lever whenever a no-label condition exists. 75
27. In a labeling machine, a cam shaft, a glue drum, a label hopper and a package feeder intermittently operated from said shaft, a label presser mounted to move towards and away from the glue drum, a cam on said cam shaft and a cam lever actuated by said cam for operating said label presser, a no-label detector comprising a rock shaft having a finger disposed for actuation by the labels upon the glue drum, a locking dog on 80 said rock shaft, a pivoted latch lever having a locking notch adapted to receive said dog, a cam on the cam shaft for raising said latch lever relative to said dog, a retarding latch carried by said latch lever and normally disposed out of the path of the cam lever which actuates said label presser, but movable into interfering relation to said lever whenever a no-label condition exists. 85
28. In a labeling machine, a continuously driven cam shaft, a glue drum intermittently revolved therefrom, a label feeder and a package feeder intermittently operated from a cam on said cam shaft, a label presser pivoted to swing towards and from the glue drum, a cam lever for actuating said label presser, a cam on the cam shaft operating said cam lever, a no-label detector, a latch lever, a cam on the cam shaft for moving said latch lever relative to the no-label detector, a retarding latch carried by said latch lever and normally disposed out of the path of the label presser actuating lever, but movable into the path of said lever whenever a no-label condition exists, a rotatable control device for the package feeder and an operative connection from the label presser actuating lever to the said device effective whenever a no-label condition exists to ac- 90 95 100 105 110 115 120 125

tuate said device and prevent operation of the package feeder.

29. In a labeling machine, in combination, a label feeder, a package feeder, and a glue drum, a label presser pivoted to swing towards and away from the glue drum, a rotatable control device dominant upon the package feeder, a clutch therefor, a no-label detector effective upon failure of the label

10 feed to prevent operation of the label presser and to actuate the rotatable package feed control device whereby to render ineffective the package feeder, a clutch shifting mechanism to disconnect the drive for

15 the rotatable package feed control device when a no-package condition exists, and a no-package detector associated with the package feeder for actuation by each package as it is placed thereon and effective when

20 a no-package condition exists to prevent operation of the package feeder and to disconnect the drive for the rotatable package feed control device.

30. In a labeling machine, in combination, 25 a package feeder, a label feeder, and a glue drum, a label presser pivoted to swing towards and away from the glue drum, a rotatable control device dominant upon the package feeder, a clutch therefor, a no-label

30 detector effective upon failure of the label feed to prevent operation of the label presser and to actuate the rotatable package feed control device whereby to render ineffective the package feeder, a clutch shifting mecha-

35 nism to disconnect the drive for the rotatable package feed control device when a no-package condition exists, a lock to prevent operation of the no-label detector when a no-package condition exists, and a no-

40 package detector associated with the package feeder for actuation by each package as it is placed thereon and effective when a no-

45 package condition exists to prevent operation of the package feeder, apply the no-label detector lock, and disconnect the drive for the rotatable package feed control device.

31. In a labeling machine, in combination, 50 a label feeder, a package feeder, and a glue drum, a label presser pivoted to swing towards and away from the glue drum, a rotatable control device dominant upon the package feeder, a clutch therefor, a no-label

55 detector effective upon failure of the label feed to prevent operation of the label presser and to actuate the rotatable package feed control device whereby to render ineffective the package feeder, a lock to prevent rotation of the label feeder when a no-package condition exists, a clutch shifting mechanism

60 to disconnect the drive for the rotatable package feed control device when a no-package condition exists, a lock to prevent operation of the no-label detector when a no-

65 package condition exists, and a no-package detector associated with the package

feeder for actuation by each package as it is placed thereon and effective when a no-package condition exists to prevent operation of the package feeder, to apply the glue drum, label feeder, and no-label detector 70 locks and to disconnect the drive for the rotatable package feed control device.

32. In a labeling machine, in combination, a cam shaft, a label feeder, a package feeder, and a glue drum intermittently operated 75 from said shaft, a label presser pivoted to swing towards and away from the glue drum, a label gripper movable towards and from the glue drum, means for opening and closing said label gripper to grasp and re-

80 lease the label, a rotatable control device for the package feeder, a clutch therefor, a no-label detector effective upon failure of the label feed to prevent the operation of the label presser and to actuate the rotatable 85 package feed control device whereby to render ineffective the package feeder, a lock to prevent rotation of the glue drum when a

no-package condition exists, a lock to prevent operation of the label gripper closing 90 when a no-package condition exists, a clutch shifting mechanism to disconnect the drive for the rotatable package feed control device when a no-package condition exists, a lock to prevent operation of the no-label detector 95

when a no-package condition exists, and a no-package detector associated with the package feeder for actuation by each package as it is placed thereon and effective when a no-

100 package condition exists to prevent operation of the package feeder to apply the glue drum, label feeder, label gripper and no-label detector locks and to disconnect the drive for the rotatable package feed control device.

105 33. In a labeling machine, a glue drum, a label feeder, a package feeder, a pawl and ratchet mechanism for intermittently operating said package feeder, a pivoted label presser movable towards and from said glue drum, a no-label detector associated with the glue drum and effective when a no-label condition exists to prevent operation of said label presser, a rotatable control device for the package feeder, an arm carrying a 110 ratchet shield and disposed for actuation by said control device to interpose said shield between the feed ratchet and the feed pawl for the package feeder whenever a no-label condition exists, and an operative connection from the label presser to said control device for actuating said device.

115 34. In a labeling machine, a glue drum, a label feeder, a package feeder, a pawl and ratchet mechanism for intermittently operating said package feeder, a pivoted label presser movable towards and from said glue drum, a no-label detector associated with the glue drum, and effective when a no-label condition exists to prevent operation of said 120

125 label presser, a rotatable control device for the package feeder, an arm carrying a ratchet shield and disposed for actuation by said control device to interpose said shield between the feed ratchet and the feed pawl for the package feeder whenever a no-label condition exists, and an operative connection from the label presser to said control device for actuating said device.

130 35. In a labeling machine, a glue drum, a label feeder, a package feeder, a pawl and ratchet mechanism for intermittently operating said package feeder, a pivoted label presser movable towards and from said glue drum, a no-label detector associated with the glue drum, and effective when a no-label condition exists to prevent operation of said

- label presser, a rotatable control device for the package feeder, an arm carrying a ratchet shield and disposed for actuation by said control device to interpose said shield between the feed ratchet and the feed pawl for the package feeder whenever a no-label condition exists, and an operative connection from the label presser to said control device for actuating said device, a clutch shifting mechanism for disconnecting the drive for said rotatable package feed control device, a no-package detector associated with said package feeder, a second arm carrying a ratchet shield and controlled from said no-package detector and effective whenever a no-package condition exists to interpose said shield between the feed ratchet and the feed pawl for the package feeder to prevent operation of the package feeder, and an operative connection from said second shield-carrying arm to the clutch shift mechanism for the rotatable package feed control device to simultaneously disconnect the drive for said device.
35. In a labeling machine, a glue drum, a label feeder, a package feeder, a pawl and ratchet mechanism for intermittently operating said package feeder, a pivoted label presser movable towards and from said glue drum, a no-label detector associated with said glue drum, and effective when a no-label condition exists to prevent operation of said label presser, a rotatable control device for the package feeder, an arm carrying a ratchet shield and disposed for actuation by said control device to interpose said shield between the feed ratchet and the feed pawl for the package feeder whenever a no-label condition exists, an operative connection from the label presser to said control device for actuating said device, a clutch shifting mechanism for disconnecting the drive for said rotatable control device, a lock for holding out of operation said no-label detector, a no-package detector associated with said package feeder, a second arm carrying a ratchet shield and controlled from said no-package detector and effective whenever a no-package condition exists to interpose its shield between the feed ratchet and the feed pawl for the package feeder to prevent operation of the package feeder, a bell crank lever operatively connected with said second shield carrying arm and with the glue drum, label hopper, and no-label detector locks and with the clutch shift mechanism for the rotatable cam whereby to simultaneously actuate all of said mechanisms whenever a no-package condition exists.
37. In a labeling machine, an intermittently revolvable glue drum, a label hopper movable relative thereto, an intermittently revolvable package feed chain, a pawl and ratchet mechanism for advancing said chain, a label gripper, means for opening and closing said gripper, a glue drum lock, a label hopper lock, a lock for preventing closing of said label gripper, a no-package detector mounted adjacent the last package space of the package feed chain, a ratchet shield carrying arm controlled from said no-package detector and effective whenever a no-package condition exists to interpose its shield between the feed ratchet and the feed pawl for the package chain, and an operative connection from said shield-carrying arm to the glue drum, label hopper, and gripper locks for simultaneously applying said locks whenever a no-package condition exists.
38. In a labeling machine, an intermittently revolvable glue drum, a label hopper movable relative thereto, an intermittently revolvable package feed chain, a pawl and ratchet mechanism for advancing said chain, a glue drum lock, a label hopper lock, a no-package detector mounted adjacent the last package space of the package feed chain, a ratchet shield carrying arm controlled from said no-package detector and effective whenever a no-package condition exists to interpose its shield between the feed ratchet and the feed pawl for the package chain and pre-
- 60 65 70 75 80 85 90 95 100 105 110 115 120 125 130

vent operation of said chain, and an operative connection from said shield carrying arm to the glue drum and label hopper locks to simultaneously apply said locks whenever a no-package condition exists.

39. In a labeling machine, a rotatable disc having a driving opening and a locking notch, a driving member fast on the disc shaft, a collar slidable on the hub of the driving member and having a driving pin disposed to engage in the driving opening of said disc, a clutch yoke pivoted between its ends and engaging said collar at one end, a yoke shifting mechanism, a locking pin carried by said clutch yoke above its pivot and disposed to engage in said locking notch, and means for actuating said yoke shifting mechanism to disconnect the drive for said rotating disc, such motion of the yoke automatically engaging the locking pin in the locking notch of said disc.
40. In a labeling machine, intermittently operated label and package feeders, a rotatable package feed control device comprising a rotatable disc having a series of driving openings and a series of locking notches, a driving member fast on the disc shaft, a collar slidable on the hub of said driving member and having a driving pin disposed to engage in one of the driving openings of said disc, a clutch yoke pivoted between its ends and engaging said collar at one end, a yoke shifting mechanism, a locking pin carried by said clutch yoke above its pivot and disposed to engage in one of said locking notches, a no-label detector effective whenever a no-label condition exists to actuate said package feed control device and prevent operation of the package feeder, a no package detector, and operative connections from said no package detector to said yoke shifting mechanism, for rocking said clutch yoke in a direction to withdraw the driving pin from the driving opening of said rotating disc whenever a no-package condition exists, such motion of the yoke automatically engaging the locking pin in one of the locking notches of said disc.
41. In a labeling machine, a glue drum, a label feeder, a package feeder, means for intermittently operating said elements, a package feed control device comprising a rotatable disc having a series of driving openings and a series of peripheral locking notches, a driving member fast on the disc shaft, a collar slidable on the hub of the driving member and having a driving pin disposed to engage in one of the driving openings of said disc, a clutch yoke pivoted between its ends and engaging said collar at its lower end, a yoke shifting mechanism, a locking pin carried by said clutch yoke above its pivot and disposed to engage in one of said locking notches, a cam associated with said disc, a cam dog pivotally mounted on said disc, a no-label detector effective whenever a no-label condition exists to move said dog into the path of said cam and project the cam beyond the periphery of said disc, a cam lever held against the periphery of said disc for actuation by said cam, operative connections from said cam lever to the package feeder operating mechanism for preventing operation of the package feeder whenever a no-label condition exists, a no package detector associated with the package feeder, and operative connections from said no-package detector to said yoke shifting mechanism effective whenever a no-package condition exists to rock said yoke in a direction to withdraw the driving pin from the rotatable disc, such motion automatically engaging the locking pin with a locking notch of said disc.
42. In a labeling machine, a glue drum, a label hopper, an intermittently operable package feed chain, a driving mechanism for said package feed chain, a package feed control device comprising a rotatable disc having a series of cam actuating dogs pivotally mounted thereon, a series of pivotally mounted cams normally disposed within the periphery of said disc, a cam throw-off lever having a dog actuating pin, a no-label detector operatively connected with said lever and effective whenever a no-label condition exists to bring said actuating pin into the path of one of said dogs whereby said dog will project one of the series of cams beyond the periphery of the rotating disc, and a cam lever normally held towards the periphery of said disc and effective, upon actuation by one of said cams to render ineffective the package feed chain driving mechanism.
43. In a labeling machine, in combination, a label feeder, and a package feeder, a glue drum associated with said label feeder, a label presser movable relative to said glue drum, a no-label detector controlled by the presence of a label upon the glue drum, operative connections from said detector to said label presser for holding the label presser out of operation whenever the label feed fails, an automatic package feed control device operatively connected with the lock-out mechanism for said label presser, means controlled from said package feed control device for preventing operation of the package feeder whenever the label feed fails, a package detector associated with said package feeder, and a safety mechanism automatically applied whenever the package feed fails and effective to prevent operation of the label feeder.
44. In a labeling machine, in combination, a label feeder, a glue drum, a package feeder, and a label presser, a no-label detector effective upon failure of the label feed to prevent operation of the label presser and

package feeder, and a no-package detector effective upon failure of the package feed to prevent operation of the label and package feeders.

45. In a labeling machine, intermittently operable label and package feeders, a no-label detector, a no-package detector, and operative connections from said no-package detector to said no-label detector for automatically rendering said no-label detector ineffective whenever a no-package condition exists.

46. In a labeling machine, a label and a package feeder, intermittent operating mechanisms therefor, a no-label detector, a no-package detector, operative connections from said no-package detector to said no-label detector for automatically rendering said no-label detector ineffective whenever a no-package condition exists, and operative connections from said no-package detector to the operating mechanism for the package feeder for automatically rendering the operating mechanisms for the package and label feeders ineffective whenever a no-package condition exists.

47. In a labeling machine, a label and a package feeder, intermittent operating mechanisms therefor, a rotatable control device for said package feeder operating mechanism, a no-label detector, a no-package detector, operative connections from said no-package detector to said no-label detector for automatically rendering said no-label detector ineffective whenever a no-package condition exists, and operative connections from said no-package detector to said control device for preventing rotation of said device whenever a no-package condition exists.

48. In a labeling machine, a label and a package feeder, intermittent operating mechanisms therefor, a no-package detector, and an operative connection from said detector to the package feeder operating mechanism for rendering said mechanism ineffective whenever a no-package condition exists.

49. In a labeling machine, a label and a package feeder, intermittent operating mechanisms therefor, a no-package detector, and operative connections from said detector to the operating mechanisms for the label and package feeders for rendering said mechanisms ineffective whenever a no-package condition exists.

50. In a labeling machine, an intermittently revoluble glue drum, an intermittently operable package feeder, a no-package detector, and a glue drum lock operatively connected with said detector and automatically applied whenever a no-package condition exists.

51. In a labeling machine, an intermittently revoluble glue drum, an intermittently operable label gripper, means for automatically opening and closing said label gripper,

an intermittently operable package feeder, a no-package detector, and a glue drum lock and a lock to prevent closing of the label gripper, both operatively connected with said detector and automatically applied whenever a no-package condition exists.

52. In a labeling machine, an intermittently revoluble glue drum, an intermittently operable label gripper, means for automatically opening and closing said label gripper, intermittently operable label and package feeders, a no-package detector, and a glue drum lock, a label feeder lock and a lock to prevent closing of the label gripper, all operatively connected with said detector and automatically applied whenever a no-package condition exists.

53. In a labeling machine, an intermittently operable label feeder, an intermittently operable package feeder, a no-package detector, a locking mechanism for the label feeder, and operative connections from said no-package detector to said locking mechanism automatically effective to apply said locking mechanism whenever a no-package condition exists.

54. In a labeling machine, a glue drum, a label gripper movable towards and from said glue drum, means for closing said gripper to grasp a label at the glue drum and for opening said gripper to release the label after it has been stripped from the drum, an intermittently operable package feeder, a no-package detector, a lock for preventing said gripper from closing, and operative connections from said no-package detector to said lock for automatically applying said lock whenever a no-package condition exists.

55. In a labeling machine, a glue drum, a label feeder, a lock therefor, a no-label detector, a lock therefor, a label gripper movable towards and from said glue drum, means for closing said gripper to grasp a label at the glue drum and for opening said gripper to release the label after it has been stripped from the drum, an intermittently operable package feeder, a no-package detector, a lock for preventing said gripper from closing, and operative connections from said no-package detector to all of said locks for automatically and simultaneously applying said locks whenever a no-package condition exists.

56. In a labeling machine, a continuously driven cam shaft, a glue drum shaft intermittently revolved from said cam shaft, a label hopper, a lock for said hopper, operative connections from said cam shaft to said hopper for intermittently raising and lowering said hopper relative to said glue drum including elevating springs for raising said hopper towards the glue drum, a system of levers associated with the hopper for opposing the lifting movement of said hopper, a cam on the cam shaft operative

- upon said lever system to permit the hopper elevating springs to function, a package feed mechanism, a no-package detector and operative connections from said detector to said
- 5 label hopper lock for automatically applying said lock upon failure of the package feed whereby to prevent feeding movement of the label hopper so long as the no-package condition exists.
- 10 57. In a labeling machine, a continuously driven cam shaft, a glue drum shaft intermittently revolved from said cam shaft, a glue drum lock, a label hopper, a lock for said hopper, operative connections from said cam shaft to said hopper for intermittently raising and lowering said hopper relative to said glue drum including elevating springs for raising said hopper towards the glue drum, a system of levers associated
- 15 with the hopper for opposing the lifting movement of said hopper, a cam on the cam shaft operative upon said lever system to permit the hopper elevating springs to function, a package feed mechanism, a no-
- 20 package detector, and operative connections from said detector to said glue drum and label hopper locks for automatically applying said locks upon failure of the package feed whereby to prevent rotation of the glue
- 25 drum and feeding movement of the label hopper so long as the no-package condition exists.
- 30 58. In a labeling machine, a continuously driven cam shaft, a glue drum shaft intermittently revolved from said cam shaft, a label hopper, operative connections from said cam shaft to said hopper for intermittently raising and lowering said hopper relative to said glue drum including elevating
- 35 springs for raising said hopper towards the glue drum, a system of levers associated with the hopper for opposing the lifting movement of said hopper, a cam on the cam shaft operative upon said lever system to
- 40 permit the hopper elevating springs to function, a package feed mechanism, a no-label detector effective upon failure of the label feed to render ineffective said package feed mechanism, a lock for said no-label detector, a no-package detector and operative connections from said no-package detector to said no-label detector lock for automatically applying said lock upon failure of the package feed whereby to prevent said no-
- 45 label detector from functioning as long as the no-package condition exists.
- 50 59. In a labeling machine, a continuously driven cam shaft, a glue drum shaft intermittently revolved from said cam shaft, a glue drum lock, a label hopper, a lock for said hopper, operative connections from said cam shaft to said hopper for intermittently raising and lowering said hopper relative to said glue drum including elevating
- 55 springs for raising said hopper towards the
- 60 glue drum, a system of levers associated with the hopper for opposing the lifting movement of said hopper, a cam on the cam shaft operative upon said lever system to permit the hopper elevating springs to function, a package feed mechanism, a no-label detector effective upon failure of the label feed to render ineffective said package feed mechanism, a lock for said no-label detector, a no-package detector, and operative connections from said no-package detector to said label hopper, and no-label detector locks for automatically applying said locks.
- 65 60. In a labeling machine, a glue drum and a label feeder operating in timed relation to each other, a package feeder, a pawl and ratchet operating mechanism for said package feeder, a pawl lever carrying said pawl, means for rocking said lever, a spring-tensioned arm carrying a ratchet shield and a cam piece, a bell crank lever having a latching point adapted to play between said shield carrying arm and said cam piece, and a no-package detector normally latched to said latch dog and disposed in the path of the entering package on said package feeder for actuation thereby and effective upon such actuation to withdraw the latch dog from the bell crank lever whereby the latching point of said lever will be interposed in the path of the ratchet shield arm to prevent said shield from covering the feed ratchet.
- 70 61. In a labeling machine, a label feeder and a package feeder, operating mechanisms therefor, a no-package detector, and operative connections from said detector to the operating mechanism for the label feeder, said connections automatically effective independently of the quantity of packages on the package feeder to render the operating mechanism for the label feeder ineffective whenever the package feeder fails to have a package in position to receive the label intended for it.
- 75 62. In a labeling machine, the combination with a label feeder, a label presser, and mechanism for operating said elements in timed relation to each other, of means for automatically preventing operation of the label presser upon a failure of label feed, a semi-dominant hand control for deliberately producing a no-label condition, and a dominant hand control for overcoming such condition.
- 80 63. In a labeling machine, the combination with a label feeder, and a label presser, and mechanism for operating said elements in timed relation to each other, of a no-label detector automatically effective upon a failure of label feed to prevent operation of said label presser.
- 85 64. In a labeling machine, the combination with an intermittently operable label feeder, and an intermittently operable label presser, of a no-label detector, and a latch controlled

by said detector and effective to prevent operation of said label presser upon a failure of label feed.

65. In a labeling machine, in combination, 5 a label feeder, a label presser, a no-label detector effective upon failure of the label feed to prevent operation of the label presser, and a no-package detector effective upon failure of the package feed to prevent operation of 10 the label feeder.

66. In a labeling machine, a glue drum, an intermittently operable label feeder movable towards and away from said glue drum, an intermittently operable package feeder, a 15 no-package detector, a locking mechanism for the label feeder, and operative connections from said no-package detector to said locking mechanism automatically effective to apply said locking mechanism and lock the 20 label feeder away from the glue drum whenever a no-package condition exists.

67. In a labeling machine, a glue drum, a label hopper movable towards and away from the glue drum, a spring-tensioned lifting plunger for operating said label hopper, an actuating lever for said plunger, an intermittently operable package feeder, a no-package detector, and a latch operatively connected to said no-package detector and 30 automatically effective whenever a no-pack-

age condition exists, to move said latch into an interfering position relative to said actuating lever for the label hopper whereby to lock said label hopper against movement towards said glue drum. 35

68. In a labeling machine, a package feeder, a pawl and ratchet mechanism for intermittently operating said feeder, a ratchet shield, a no-package detector, and operative connections from said detector to said shield 40 for moving said shield into position to render said pawl and ratchet operating mechanism ineffective whenever a no-package condition exists.

69. In a labeling machine, the combination 45 with an intermittently revoluble glue drum, an intermittently operable label feeder, an intermittently operable label presser, and an intermittently revoluble package feeder, and means for intermittently operating said elements in timed relation to each other, of means automatically applied upon a failure of label placement on the glue drum to prevent operation of the label presser and means automatically applied upon a failure 50 of package placement on the package feeder 55 to prevent operation of the label feeder.

In testimony whereof I affix my signature.

JAMES A. BUTLER.
